UNITED STATES PATENT OFFICE.

AUGUSTIN HENTSCHEL, OF BERLIN, GERMANY.

STREET-CLEANING ROLLER.

SPECIFICATION forming part of Letters Patent No. 664,861, dated January 1, 1901.

Application filed March 12, 1900. Serial No. 8,354. (No model.)

To all whom it may concern:

Be it known that I, AUGUSTIN HENTSCHEL, manufacturer, a subject of the King of Prussia, Emperor of Germany, and a resident of Berlin, Germany, have invented certain new and useful Improvements in Street-Cleaning Rollers; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 My invention consists of a new and useful roller for street-cleaning carts or other similar devices and differs from the rollers heretofore used for such purposes through its particular formation and means for holding the 20 rubber blades or "sweeps."

The rollers at present employed, consisting of massive wooden cylinders with rubber blades fitted into screw-thread-like grooves cut in the surface of the cylinder, have serious disadvantages. First, these rollers are very heavy, requiring large counterweights in order to be easily raised and lowered, and, second, after short use they absorb so much moisture from the sprinkled streets that they 25 far overbalance their counterweights, thus making them heavy to operate and adding considerable strain to the cart. In absorbing the water they warp or twist so that, thirdly, the rubber blades become loosened, 30 thus adding further to the difficulty met with originally in fastening these blades in their grooves. The roller often becomes loose on the axle. In my invention, however, these difficulties are avoided, as will be hereinafter 35 explained.

40 In the accompanying drawings, in which similar letters of reference refer throughout to similar parts, Figure 1 illustrates a side view of a roller with spiral-set blades embodying my invention. Fig. 2 is a front view of Fig. 1. Fig. 3 shows the roller with blades extending longitudinally.

45 In the construction of my invention I employ an axle *a*, upon which are securely mounted a plurality of disks *b*, each of which has a toothed periphery *c*. Three of such disks may be employed, as illustrated, or if a

roller is desired of shorter length the middle one may be omitted.

The roller-body itself consists of a plurality 55 of strips *d*, made of wood or any other desirable material which can be easily made watertight and be of light weight. These strips are arranged so as to snugly fit into the toothed disks aforesaid, while rubber blades *f* wedge 60 tightly between each of the said strips and extend outwardly a predetermined distance beyond the latter.

The several parts of the roller can be assembled as shown in Fig. 1, where the different strips, with their adjacent blades, present a spiral or screw-threaded-like roller, or they may be assembled in the order shown in Fig. 3, where the disks are secured to the axle *a*, with their teeth *c* registering, and the strips, 70 with the blades, carried between the thus-registering teeth.

The strips *d* and rubber blades *f* instead of being parallel with the roller shaft or spindle may be arranged spirally about the same. 75 This can be done in two ways. The toothed disks *b* may, for instance, be secured to the axle or shaft *a*, so that the spaces between their teeth will be in line—that is to say, on lines parallel with said shaft—and the strips *d* and *f* inserted into spaces between the teeth of the several disks out of line with one another, the pitch of the blades and strips depending, of course, upon the distance between the spaces in one end disk, in which the 85 ends of the two strips *d* and the intermediate rubber blade *f* are seated, from the corresponding spaces in the intermediate and opposite end disks *b*, as will be readily understood, or this may be effected by fastening 90 all of the said strips and blades into position in the form shown in Fig. 3, fastening one end disk tightly to the axle and then giving a half-turn to the other end disks before fastening the latter. In either case the strips wedged 95 between the teeth *c* and the blades *f* wedged between the said strips are tightly held in position, the compactness of which is increased by giving them a spiral-like twist.

The strips of wood *d* are or may be waterproofed by any well-known process in order to prevent absorption of moisture and consequent increase in weight, as well as warping and the difficulties arising therefrom. It is

evident that should one of the rubber blades or one of the strips *d* require removal this can readily be done and another substituted, as the said strips can readily be driven out of their seats.

Having now described my invention, what I claim as new, and desire to protect by Letters Patent, is—

1. A new and useful roller for street-cleaning carts consisting of disks and a plurality of similarly-formed strips and rubber blades adapted when being placed about said disks in their relative positions to firmly wedge themselves into a compact whole, substantially as described.

2. A new and useful roller for street-cleaning carts having an axle, toothed disks mounted thereon, strips extending from disk to disk and fastened between the teeth thereof, and rubber blades adapted to be firmly held in position between and by said strips, substantially as described. 20

In testimony that I claim the foregoing as my invention I have signed my name in presence of two subscribing witnesses.

AUGUSTIN HENTSCHEL.
